POSITION INDICATOR

George Peterson, Jr., Wayne, Pa., assignor to Penn Keystone Corporation, West Conshohocken, Pa., a corporation of Pennsylvania

Application February 21, 1957, Serial No. 641,639

5 Claims. (Cl. 340—378)

The present invention relates to new and useful improvements in electro-magnetically operated position indicators which are operable to indicate the position of an element, for example, to indicate the "up" or "down" position of aircraft landing gear. More particularly the present invention relates to structural improvements in an electro-magnetically actuated position indicator of this type wherein circuits remotely opened and closed will cause the position indicator to be actuated from a central neutral position to one or another extreme limit positions to indicate the position of the movable element. This invention is an improvement in my position indicator shown and described in my prior Patent No. 2,655,647, issued October 13, 1953.

One object of the present invention is to provide an electro-magnetically operated position indicator having novel structural features whereby the position indicator may be assembled rapidly and easily maintained in the assembled position.

Another object of the present invention is to provide an electro-magnetically operated position indicator in which the indicator may be readily set at a neutral position by a relatively simple adjustment prior to assembly of the indicator.

A still further object of the present invention is to provide an electro-magnetically operated position indicator which is of relatively compact construction and may be economically manufactured and assembled from inexpensive fabricated parts and which will be sturdy and reliable in use.

These and other objects of the present invention and the various features and details of the operations and construction thereof are hereinafter more fully set forth and described with reference to the accompanying drawings, in which:

Fig. 1 is a plan view partially in section of the position indicator of the present invention;

Fig. 2 is a longitudinal sectional view taken on line 2—2, Fig. 1, illustrating the construction of the position indicator of the present invention;

Fig. 3 is a fragmentary sectional view taken on line 3—3, Fig. 2, illustrating the mounting of the armature assembly of the present invention;

Fig. 4 is a fragmentary side elevational view of a portion of the front end of the position indicator of the present invention illustrating the means for positioning the frame members wherein the housing of the indicator;

Fig. 5 is an exploded perspective view illustrating the construction of the rear plate and opposite side frame members of the present invention;

Fig. 6 is a perspective view of the armature and indicator assembly of the position indicator;

Fig. 7 is an enlarged side elevational view of the means for adjustably securing the inner end of the centering spring to the armature shaft;

Fig. 8 is a plan view of the indicator prior to being bent and secured to the armature assembly; and

2

Fig. 9 is a schematic diagram of the electrical circuit for the position indicator.

Referring more specifically to the drawings and particularly Figs. 1 and 2 thereof, reference numeral 10 designates generally a rectangular cup-shaped housing for the indicator having opposite side walls 11, 11, top and bottom walls 12, 12 and a front wall 13. A glass or other transparent window member 14 is securely positioned in the center of the front wall 13 of the housing. The housing is completely enclosed and made air-tight by means of a generally rectangular rear wall 15 which is positioned in engagement with the inner edges of the side, top and bottom walls of the housing and secured to the housing, for example, by means of soldering as indicated in Figs. 1 and 2.

Formed integrally with the rear wall 15 of the housing and projecting inwardly of the housing is a side frame member 16, formed as illustrated in Fig. 5 of the drawings. A second side frame member 17 is mounted in spaced parallel relation with the side member 16 interiorly of the housing 10 by means of a plurality of tie rods 18.

In accordance with the present invention an armature assembly 21 is pivotally mounted between the opposite side frame members 16 and 17 for rotary movement between a central neutral position and opposite limit positions. The armature assembly 21 consists of a frame member 22 terminating at its outer periphery in cross-wise extending supporting arms 23, 23 and having a pair of arcuate armature members 24, and 25 at opposite sides thereof. The frame member 22 is mounted on a shaft 26 which is pivotally mounted in bearings 27, 27 formed in the opposite side frame members 16 and 17. A substantially arcuate indicator plate 28 is secured between the cross arms 23, 23 of the armature assembly, for example by means of rivets 29, on the opposite side of the armature assembly from the arcuate armature members 24 and 25 to provide a complete armature and indicator assembly which is statically and dynamically balanced about the axis of the shaft 26.

The armature and indicator assembly as shown in Fig. 5 is positioned between the two side frame members 16 and 17 with the shaft 26 positioned in the side frame bearings 27, 27 prior to completely assembling the side frame members. The side frame members are then connected together by means of the tie rods 18 and secured to the tie rods 18, for example, by means of fillister-head bolts 31. The indicator plate 28 is positioned forwardly of the side frame members so that when the side frame members are inserted within the housing 10 the indicator plate is adjacent the window 14 in the front wall of the housing.

According to the present invention the indicator and armature assembly is mounted on the side frame members for movement from a central neutral position to opposite limit position. The indicator is maintained in its central neutral position by means of a flat wire coil spring 32 having one end thereof interconnected with a lug 33 projecting inwardly from the side frame member 17 and the other end thereof secured to a split collet which is carried by the indicator shaft 26. The collet 34 frictionally embraces the indicator shaft 26 and may be adjusted by being rotated about the indicator shaft to adjustably position the indicator 28 relative to the front window 14 of the housing so that the center portion of the indicator 28 is opposite the central portion of the window 14 when the armature is in its neutral position. Riveted to the side frame members 16 and 17 directly opposite each other are two electro-magnetic solenoids 36 and 37 respectively. The solenoid 36 has a central core member 38 formed of molded nylon or other insulating material having a central opening 39

therein operable to receive the arcuate armature member 25 upon rotation of the armature in one direction, and a toroidal coil 41 is wound about the core member 38. The solenoid 37 is formed in a manner similar to that of the solenoid 36 and also comprises a core and toroidal coil. A central opening 42 is provided in the core of the coil 37 operable to receive the armature member 24 upon rotation of the armature in the opposite direction. When the solenoid 36 is energized the armature member 25 will be pulled inwardly of the central opening 39 of the armature 36 by means of the electro-magnetic field created by the solenoid 36 and the indicator will be rotated in the counterclockwise direction relative to Fig. 2 from the central neutral position to one of its opposite limit positions. In a similar manner, when the solenoid 36 is deenergized and the solenoid 37 energized the armature member 24 will be pulled inwardly of the central opening 42 of the armature 37 rotating the armature and indicator assembly in the clockwise direction relative to Fig. 2 from the central neutral position to its opposite limit position.

The solenoids 36 and 37 are electrically connected with an external source of power by means of three electrically insulated conductors 43, 44 and 45 which extend through an externally threaded nipple 46 carried by the housing rear wall 15. The conductors 43, 44 and 45 extend outwardly beyond the nipple 46 and are engaged within sockets of a conventional plug 47. The plug 47 is maintained in contact with the conductors by means of a knurled nut 48 engaging the plug 47 and threaded onto the nipple 46. Wires are soldered upon the inner end of the conductors 43, 44 and 45 and are electrically connected with the coils of the solenoid 36 and 37 as more fully described hereinafter.

Fig. 7 illustrates a schematic wiring diagram of the position indicator of the present invention wherein the indicator may be moved from its central neutral position to its opposite limit positions. The circuit illustrated in Fig. 9 is specifically designed to indicate the position of the wheels of an aircraft and to this end, a pair of switches 51 and 52 are provided which may be closed by a switch actuating member 53 interconnected with the aircraft landing gear. When the switch 51 is closed the coil 36 will be energized thereby rotating the armature in the counterclockwise direction relative to Fig. 2 to move the indicator to a position indicating the "up" position of the wheels. Alternatively, when the switch 52 is closed the armature 37 will be energized moving the indicator to a position indicating the "down" position of the wheels. When the indicator is in its central neutral position the wheels are midway between their up and down position and both switches 51 and 52 are opened. A resistor 54 may be provided in the electrical circuit and mounted interiorly of the housing of the position indicator. The resistor 54 will be used in series with the solenoids 36 and 37 when the position indicator is used with a conventional 110 volt power supply. If the position indicator is to be used with a lower voltage power supply, for example, a 28 volt power supply which is common in most airplanes, the resistor 54 may be omitted from the circuit.

An important feature of the present invention is the provision of means on the side walls of the housing 10 to properly position the armature and the indicator assembly within the housing 10. To this end, the forward central portions of the side walls 11, 11 are indented as indicated at 56 in Figs. 1 and 4 of the drawings with generally U-shaped indentations directly opposite one another to provide generally U-shaped locating shoulders 57, 57 interiorly of the housing 10.

During assembly of the position indicator of the present invention when the rear wall of the indicator is being inserted in position at the rear of the casing 10 the fillister head bolts 31, 31 which secure the forward ends of the side frame members 16 and 17 together are received

within the U-shaped locating shoulders 57, 57 formed interiorly of the housing side walls and thereby position and support the forward end of the side frame members 16 and 17 relative to the casing 10 and front window 14 of the casing. By this construction, after the collet 34 has been adjusted to properly center the indicator 28 relative to the side frame members 16 and 17, the side frame members 16 and 17 are positioned in the desired location relative to the window 14, so that the indicator is properly viewed through the window 14. After this position indicator has been completely assembled, a vacuum is created within the interior of the indicator by exhausting the air in the indicator through a tube 58 secured to the rear wall 15 and upon completion of the formation of the vacuum the outer end of the tube 58 is sealed as shown at 59 in Fig. 2.

From the foregoing it will be observed that the present invention provides a novel position indicator having novel structural features whereby the position indicator may be assembled rapidly and easily and maintained in the assembled position, and in which the indicator may be readily set at a central neutral position by a relatively simple adjustment prior to assembly. In addition, it will be observed that the present invention provides a novel position indicator which is of relatively simple construction and may be manufactured and assembled easily and cheaply.

While particular embodiments of the present invention have been illustrated and described herein it is not intended to limit the invention to such a disclosure and changes and modifications may be incorporated and embodied therein within the scope of the following claims.

I claim:

1. An electro-magnetic indicator comprising a generally rectangular housing having front and side walls, a window in the front wall of said housing, a first side frame member for the indicator positioned within said housing, a second side frame member carried by said first side frame member in spaced parallel relation therewith, mounting means to position said side frame members relative to said housing, an armature assembly pivotally mounted between said side frame members for rotary movement from a central neutral position to opposite limit positions, an indicator carried by said armature assembly adjacent said housing window operable to indicate the position of said armature, a centering spring operable to resiliently maintain said armature in its central neutral position, a spring retaining member carried by said armature, said retaining member mounted for adjusting movement with respect to the armature to permit adjustment of said central neutral position, and electro-magnetically operated actuators secured to said side frame members operable to actuate said armature assembly from said central position to said opposite limit positions.

2. An electro-magnetic indicator comprising a generally rectangular housing having front and side walls, a window in the front wall of said housing, a first side frame member for the indicator positioned within said housing, a second side frame member carried by said first side frame member in spaced parallel relation therewith, mounting means to position said side frame members relative to said housing, an armature assembly pivotally mounted between said side frame members for rotary movement from a central neutral position to opposite limit positions, an indicator carried by said armature assembly adjacent said housing window operable to indicate the position of said armature, a centering spring one end thereof interconnected with said armature assembly and the other end thereof secured to side frame member operable to resiliently maintain said armature assembly in its central neutral position, a split collet frictionally engaging said armature assembly and secured to said one end of said centering spring to permit adjustment of the central neutral position of said armature, and electromagnetically operated actuators secured to said side frame members

operable to actuate said armature assembly from said central neutral position to said opposite limit positions.

3. An electro-magnetic indicator comprising a generally rectangular housing having front and side walls, a window in the front wall of said housing, a first side frame member for the indicator positioned within said housing, a second side frame member carried by said first side frame member in spaced parallel relation therewith, means forming generally U-shaped indentations projecting inwardly of said housing in opposite side walls thereof adjacent the housing front wall providing locating shoulders inwardly of said housing side walls, means interconnecting said frame members with said locating shoulders operable to position and support the forward ends of said side frame members, an armature assembly pivotally mounted between said side frame members for rotary movement from a central neutral position to opposite limit positions, an indicator carried by said armature assembly adjacent said housing window operable to indicate the position of said armature, a centering spring having one end thereof interconnected with said armature assembly and the other end thereof secured to a side frame member operable to resiliently maintain said armature in its central neutral position, means adjustably connecting said one end of said centering spring to said armature assembly to permit adjustment of said central neutral position, and electro-magnetically operated actuators secured to said side frame members operable to actuate said armature assembly from said central position to said opposite limit positions.

4. An electro-magnetic indicator comprising a generally rectangular housing having front and side walls, a window in the front wall of said housing, a first side frame member for the indicator positioned within said housing, a second side frame member carried by said first side frame member in spaced parallel relation therewith, means forming generally U-shaped indentation projecting inwardly of said housing in opposite side walls thereof adjacent the housing front wall providing locating shoulders inwardly of said housing side walls, means

interconnecting said side frame members with said locating shoulder operable to position and support the forward ends of said side frame members, an armature assembly pivotally mounted between said side frame members for rotary movement from a central neutral position to opposite limit positions, an indicator carried by said armature assembly adjacent said housing window operable to indicate the position of said armature, a centering spring having one end thereof interconnected with said armature assembly and the other end thereof secured to a side frame member operable to resiliently maintain said armature in its central neutral position, means adjustably connecting said one end of said centering spring to said armature assembly to permit adjustment of said central neutral position, and electro-magnetically operated actuators secured to said side frame members operable to actuate said armature assembly from said central neutral position to said opposite limit positions.

5. In an electro-magnetic indicator of the type described, a housing having front and side walls, a window in the front wall of said housing, a rear wall fixedly secured to said housing completely closing said housing, a first side frame member secured to said rear wall and projecting forwardly into said housing, a second side frame member carried by said first side frame member in spaced parallel relation therewith, means forming generally U-shaped indentation projecting inwardly of said housing in opposite side walls thereof adjacent the housing front wall providing locating shoulders inwardly of said housing side walls, and means interconnecting said side frame members with said locating shoulders operable to position and support the forward end of said side frame members.
